UNITED STATES PATENT OFFICE.

CHARLES H. HOFFSTETTER, OF ERIE, PENNSYLVANIA.

DESIGN FOR A FIRE-BOX OF A TUBE-HEATER.

No. 37,535.

Specification for Design.

Patented Sept. 5, 1905.

Application filed July 27, 1905. Serial No. 271,546. Term of patent 7 years.

To all whom it may concern:

Be it known that I, CHARLES H. HOFFSTETTER, a citizen of the United States, residing and having a post-office address at 631 West Eighth street, Erie, county of Erie, and State of Pennsylvania, have invented a new, original, and ornamental Design for a Fire-Box of a Tube-Heater, of which the following is a specification, reference being had to the accompanying drawing, forming part thereof.

The figure is a perspective view of a fire-box of a tube-heater, showing my design.

I claim—

The ornamental design for a fire-box of a tube-heater as shown.

CHARLES H. HOFFSTETTER.
